UNITED STATES PATENT OFFICE.

LEE THARP, OF BURLINGTON, IOWA.

AUTOMOBILE DOOR SPRING.

Application filed June 11, 1924. Serial No. 719,429.

To all whom it may concern:

Be it known that I, LEE THARP, a citizen of the United States, residing at Burlington, in the county of Des Moines and State of 5 Iowa, have invented certain new and useful Improvements in Automobile Door Springs, of which the following is a specification.

This invention appertains to automobile door appliances and more particularly to 10 hinges and the primary object of the present invention is to provide novel means for insuring the automatic closing of an automobile door after the same has been opened and thereby effectively prevent the door 15 from becoming damaged or broken off by coming in contact with extraneous objects, when the door has been inadvertently left open.

Another important object of the present 20 invention is to provide an attachment for the ordinary hinges of an automobile door, the attachment being so constructed as to resiliently engage the leaves of the hinge so as to normally urge the door to a closed 25 position.

A further object of the invention is to provide novel means for associating the attachment with a hinge, whereby the attachment can be readily and quickly placed in 30 position on the ordinary hinge or removed therefrom when so desired.

A still further object of the invention is to provide a novel spring attachment on the 35 hinges of automobile doors of the above character, which will be durable and efficient in use, one that will be simple and easy to manufacture and one which can be placed upon the market and incorporated with a hinge at a small cost.

With these and other objects in view, the 40 invention consists in the novel construction, arrangement and formation of parts, as will be hereinafter more specifically described, claimed, and illustrated in the accompanying 45 drawings, in which drawings,

Figure 1 is a perspective view of the improved attachment,

Figure 2 is a longitudinal vertical sectional view illustrating the attachment applied to 50 an ordinary type of hinge,

Figure 3 is a horizontal longitudinal sectional view showing the attachment applied to an ordinary type of hinge,

Figure 4 is a fragmentary longitudinal

horizontal section through the body of an 55 automobile showing the device connected to a hinge.

Referring to the drawings in detail, wherein similar reference characters designate corresponding parts throughout the several 60 views the letter A generally indicates the improved appliance, B of an ordinary type of butt hinge for the door C of an automobile body D.

The automobile body D can be of the usual 65 or any preferred character and has simply been shown to illustrate the use of the attachment. The hinge B as stated is of the ordinary character and embodies the usual leaves 5 and 6, which are provided at their 70 outer ends with rolled hinge barrels 7 for the reception of the usual hinge pintle 8. The leaves 5 and 6 of the hinge B at their inner ends are provided with the usual openings 9 for the reception of the retaining elements to permit the hinge to be connected 75 in the usual way to the jamb of the body and door C.

The improved attachment A comprises a case 10, which can be formed of sheet 80 metal or the like and this case 10 embodies upper and lower arms or walls 11 and 12 which are connected by an arcuate rear wall 13 and relative short side plates 14. As shown the side plates 14 are formed integral 85 with the arcuate wall 13. The top and bottom plates or arms 11 and 12 are provided adjacent to the arcuate wall 13 with openings 15 for the reception of a retaining pin 16 around which is coiled the spring 17, 90 which can be of the desired size and strength. The terminals of the spring 17 are provided with outwardly projecting arms 18, while the intermediate portion of the spring is provided with an outward projecting U shaped arm 19 which lies between 95 the arms 18.

The upper and lower walls or plates 11 and 12, in spaced relation to the openings 15 and directly in front of the side wall 14, are provided with openings 20 which are adapted to receive the usual hinge pintle 8, as will be hereinafter more fully described.

In applying the improved attachment to the hinge of an automobile door the pintle 8 is removed from the hinge and the case 10 is slipped on the hinge so as to receive the barrel 7 thereof. The upper and lower arms

18 of the spring are placed on the outer surface of one leaf, while the intermediate U shaped arm 19 of the spring is placed in engagement with the outer surface of the other leaf. The hinge pintle 8 is now placed in the openings 20 and back into the hinge barrels 7.

Now it can be seen that when the door C of an automobile is opened, that the leaves 10 5 and 6 will swing on the hinge pintle 8 in the usual manner and that the arms 18 and the arm 19 will be forced apart in opposite directions increasing the tension of the spring 17 and thus as soon as the door 15 is released, the arms of the spring will automatically return the door to its closed position. It is obvious that this will effectively prevent the automobile door from being injured by being left open and coming in 20 contact with extraneous objects such as the garage door and the like when the car is being placed in the garage.

The arms 18-18 of the spring 17 are rigidly connected together by a suitable strip 25 25 in order that spreading of the arms relative to one another and slipping thereof off of the hinge leaf will be prevented.

Changes in detail may be made without departing from the spirit or the scope of this 30 invention.

What I claim as new is,

1. The combination with a conventional hinge of the butt type including a pair of hinge leaves, barrels formed on the hinge leaves, a hinge pintle received in said barrels, of a spring attachment, for the hinge embodying a case, a spring mounted within the case, means connecting the case to the hinge pin, and arms formed on the spring 35

arranged to engage the outer faces of the 40 leaves.

2. The combination with a conventional hinge of the butt type including a pair of hinge leaves, hinge barrels formed on the leaves, a hinge pin fitted in said barrels, of an attachment for the leaves for normally urging the leaves toward each other embodying a case including upper and lower walls arranged to receive the hinge barrels and having openings formed therein registering with the hinge barrels, the openings being adapted to receive the hinge pin for connecting the case with the hinge, a coil spring fitted within and secured to the case, and arms formed on the spring normally 50 tending to move toward one another engaging the outer faces of the leaves of the hinge.

3. Attachments for hinges of the non-spring type comprising a case including an arcuate outer wall, forwardly extending upper and lower walls formed on the outer wall, and side walls connecting the outer wall and the top and bottom walls together, a pin carried by the top and bottom walls and arranged between the side walls, a spring coiled about said pin, upper and lower arms formed on the terminals of the spring, an intermediate U shaped arm formed on the spring, the upper and lower walls being provided with registering openings forwardly of the pins, and a hinge pin removably fitted in said openings.

In testimony whereof I affix my signature in presence of two witnesses.

LEE THARP.
